(57) **CLAIM**

I claim the ornamental design for a flashlight, as shown and described.

DESCRIPTION

FIG. 1 is a perspective view of the flashlight showing the new design;

FIG. 2 is a front elevational view thereof;

FIG. 3 is a rear elevational view thereof;

FIG. 4 is a left side elevational view thereof,

FIG. 5 is a right side elevational view thereof,

FIG. 6 is a top plan view thereof; and,

FIG. 7. is a bottom plan view thereof.

The broken lines shown in the drawings represent unclaimed environment and are for illustrative purposes only, forming no part of the claimed design.

1 Claim, 4 Drawing Sheets
